United States Patent Office

Des. 210,237

Patented Feb. 20, 1968

210,237

PITCHER

Robert T. Mestrovic, Chicago, Ill., assignor, by mesne assignments, to Solomon A. Weisgal, Chicago, Ill., as trustee

Filed May 16, 1967, Ser. No. 7,151

Term of patent 14 years

(Cl. D44—21)

I claim:

The ornamental design for a pitcher, as shown.
